OFF-PEAK WATER HEATING SYSTEM

Herman M. Biebel, Elgin, Ill., assignor to McGraw
Electric Company, Elgin, Ill., a corporation of
Delaware

Application March 31, 1941, Serial No. 385,979

5 Claims. (Cl. 219—39)

My invention relates to electric heating systems and particularly to off-peak water heating systems.

The main object of my invention is to provide a relatively simple and inexpensive control means for a water heating system that will delay the start of the energization of the heater for a time after the start of an off-peak period, which length of time increases with the amount of hot water in the tank at that time.

Other objects of my invention will either be apparent from a description of one form embodying my invention or will be specifically pointed out in the course of such description and set forth in the appended claims.

In the single sheet of drawings,

Figure 1 is a view showing the elements constituting the cooperating parts of my system as associated with an ordinary domestic hot water tank, the latter being shown in vertical section,

Fig. 2 is a fragmentary view of one part of the elements utilized in my system shown at the start of a heating operation,

Fig. 3 is a fragmentary view showing certain of the control parts just before the end of a heating operation, and,

Fig. 4 is a fragmentary view showing certain of the control parts just after the end of a heating operation.

Referring first to Fig. 1 of the drawing, I have there shown the usual domestic hot water tank 11 provided with a cold water inlet pipe 13 and a hot water outlet pipe 15 connected to the tank in the usual manner. I may provide a mass 17 of heat insulating material around the tank 11 which may be protected and held in proper operative position by an outer casing 19, all in a manner well known in the art. I provide further an electric heating element 21 which may be so designed and constructed as to be secured around the outside of the tank and which may be located in a tunnel member 23. While I have shown an outside heating element I do not desire to be limited thereto since the control system more particularly embodying my invention can be operatively associated with any other kind of electric tank heater.

I provide a continuously operative timing means designated generally by the numeral 25 and including an electric motor 27 which is connected to two supply circuit conductors 29 and 31 so that it may operate continuously. I provide a worm gear 33 on the shaft of the motor which worm gear is adapted to mesh with and drive a worm wheel 35. I desire to point out here that I have illustrated this continuously operative timing means generally only but I desire to provide a driving means of any kind which will cause rotation of either the worm wheel 35 or a shaft 37 through one complete revolution in

20 twenty-four hours or, stated otherwise, in one day. I desire to point out further that I have not illustrated any supporting or bearing members for the shaft 37 since these constitute no part of my invention.

I mount an arm 39, which is preferably made of electric insulating material, on the shaft 37 and I rotatably mount thereon a contact blade or arm 41 which is insulated and rotatably supported on a stud 43. The bushing surrounding the stud 43 and supporting the arm 41 may be provided with two peripherally spaced arms 45 and 47 for a purpose which will hereinafter appear.

15 I provide a pair of fixed contact members 49 and 51 spacedly mounted on the outer end of the arm 39 in a position to be engaged by the contact blade 41, as will be hereinafter set forth. The parts 41, 49 and 51 constitute an on and off switch.

20 The two fixed contact members 49 and 51 are connected with a pair of slip rings 53 and 55 insulatedly mounted on shaft 37, by conductors 57 and 59. I wish to point out that while conductors 57 and 59 are shown as apparently extending from the contact members to the slip rings disassociated from the arm 39 and the shaft 37, they will be supported by shaft 37 and arm 39 to rotate therewith, all in a manner well known in the electrical art relating to such structures.

25 Means for causing closing of the switch comprising the parts 41, 49 and 51 may include a pin 61 carried on an arm 63 to extend substantially parallel with the shaft 37. Arm 63 may be supported by a bushing 65 movably mounted on shaft 37. I have illustrated a support 67 for one end of shaft 37 but do not desire to be limited thereto. A thermally responsive member in the form of a rod 69 has its upper end fixedly held by a bracket 71 which bracket is supported by the upper end of the tank 11. While I have shown a bar or rod 69 of non-expansible material, it is obvious that I may use an expansible rod with but slight changes in the control structure. The lower end of bar 69 may be provided with teeth adapted to mesh with teeth on the one end of the bushing 65. If it be assumed that the rod 69 is made of some substantially non-expansible material, when subjected to increase of temperature, the upper end of rod 69 will be moved upwardly in accordance with the expansion of the tank 11 when filled with hot water. It is, therefore, evident that arm 63 will be caused to turn in a clockwise direction and it may be assumed, for illustrative purposes, that arm 63 and pin 61 will be moved to the positions shown in the broken lines in Fig. 1 when the tank contains a predetermined quantity of hot water which may be on the order of one-third or

one-half of its entire contents. The rod 69 may be said to respond to the average temperature of the water in the tank or to its heat condition or its heat content.

I provide a thermal heater control switch 73 which is in heat-receiving relation with the lower end portion of the tank 11 and is to be understood as being adapted to cause deenergization of the heater 21 when the tank is substantially full of hot water. Switch 73 includes a bimetal bar 75 having one end fixedly mounted, say on the tank, while the free end of bimetal bar 75 may engage with and move away from a fixed contact member 77.

I provide further an electromagnetic heater control switch including a coil 79 adapted to magnetize a movable core 81. This core is connected to an upper main contact bridging member 83 and a lower auxiliary bridging member 85 adapted, respectively, to engage with and be disengaged from fixed contact members 87 and 89.

The supply circuit conductor 29 is connected by a conductor 91 with one of the fixed contact members 87, the other fixed contact member 87 being connected by a conductor 93 with one terminal of heater 21. The other terminal of heater 21 is connected to the fixed end of bimetal bar 75. Contact member 77 of switch 73 is connected by a conductor 95 with the other supply circuit conductor 31.

A conductor 97 connects supply circuit conductor 29 with a conductor 99 ending at a contact arm 101 in engagement with slip ring 53. The other slip ring 55 is engaged by a contact arm 103 connected by conductors 105 and 107 with one terminal of coil 79. The other terminal of coil 79 is connected by a conductor 109 with that terminal of heater 21 connected to one terminal of the thermal switch 73.

Let it be assumed that the tank 11 has just been filled with cold water and that the position of switch-actuating pin 61 is that shown in full lines in Fig. 1 of the drawing. The continuously operative timer may be considered to be shown in the position which it would normally occupy just before the start of an off-peak period and, for illustrative purposes, it may be stated that an off-peak period may have a duration of eight hours and extend from 10 p. m. to 6 a. m. As will be herein-after set forth, it is possible to start operation of the heater at any time of day and it is to be understood that the positions of the continuously operative timer in which they are shown in Fig. 1 of the drawing, may be obtained, for initial use of the system, at any time of the day.

When arm 39 is caused to move in a clockwise direction, as hereinbefore set forth, arm 45 will engage the end of pin 61 and thereby cause turning movement of arms 45, 47 and 41 on pin 43 until arm 41 has been moved into engagement with fixed contact members 49 and 51, as is shown in Fig. 2 of the drawing. This will cause energization of coil 79 through the following circuit: From supply circuit conductor 29 through conductors 97 and 99, contact arm 101, slip ring 53, conductor 57 through engaged contact members 49, 41 and 51, through conductor 59, slip ring 55 and contact bar or brush 103, through conductors 105 and 107 to and through coil 79, through conductor 109, the closed thermal switch 73 and from there through conductor 95 to the other supply circuit conductor 31. This will cause energization of core 81 with attendant upward movement of the two contact bridging

members, contact bridging member 83 being moved into engagement with fixed contact members 81 to close an energizing circuit through the heater substantially as follows: From supply circuit conductor 29 and conductor 91 to and through engaged contact members 81 and 83, through conductor 93 and heater 21, through closed thermal switch 73 and from there through conductor 95 to the other supply circuit conductor 31. Energization of heater 21 will therefore be effected and heating of the water in the tank will start.

A holding circuit for maintaining the electromagnetic switch in closed position is also effected, this circuit being substantially as follows: From supply circuit conductor 29 through conductors 91 and 111 to and through the engaged contact members 89 and 85, through a conductor 113 to that end of the coil to which conductor 107 is connected, through coil 79, conductor 109, switch 73 and from there through conductor 95 to the other supply circuit conductor 31.

It is evident that the design, construction and adjustment of the component parts, particularly of the continuously operative timer, may be made such that when the tank contains a predetermined amount of cold water the thermally adjustable actuating pin 61 will be in position so that the relay energizing switch continuously moved by the timer may be closed at substantially the start of an off-peak period but will be closed later if the tank contains a lesser quantity of cold water, the primary object being to start energization of the heater and heating of the water in the tank at a time which will cause substantially all of the water in the tank to be hot just before the end of an off-peak period.

It is, of course, necessary that engagement of arm 41 with contact members 49 and 51 be broken at a time corresponding generally to the end of an off-peak period in order that the system may be ready to operate similarly at either the start of the next off-peak period or with a time delay, as set forth above. For this purpose I provide a pin 115 which is shown generally only in the various figures of the drawing but is to be understood as being properly supported to be engaged by arm 47 hereinbefore described. Fig. 3 shows the position occupied by certain parts of my control system just before the end of an off-peak period when arm 47 on its supporting arm 39 has been moved almost into engagement with fixed pin 115. Fig. 4 shows the positions of these parts when arm 47 has been moved into engagement with fixed pin 115 and has caused disengagement of contact arm 41 from the fixed contact members 49 and 51.

In case all of the water in the tank has been heated to a desired temperature, that is, substantially all of the water in the tank is hot, bimetal bar 75 will have flexed to move its free end away from the fixed contact member 77 which would also have interrupted the hereinbefore described holding circuit for the electromagnetic switch. Movement of contact arm 41 away from contacts 49 and 51 would, therefore, reset the continuously movable switch including more particularly the contact arm 41, so that at some later time, say at the start of the next off-peak period, the system would be ready to cause reenergization of the heater 21.

I provide a manually operable push button switch 117 which may be located at any convenient place in the basement or one of the rooms of a home to be operated manually by

the user of a water heating system of this kind to cause energization of the heater irrespective of the timing means. Such a condition may occur in case of sudden unexpected demands for hot water. The fixed contact members 119 and 121 of the push button switch 117 are connected to conductors 99 and 105 respectively. A contact bridging member 123 may be normally moved into engagement with the fixed contact members 119 and 121 and the hereinbefore described energizing circuit through coil 79 will be effected although the contact bars 101 and 103 and the slip rings and the conductors to the fixed contact members to the continuously movable switch will not be in electric circuit as hereinbefore described.

Should it happen that all of the water in the tank is hot an appreciable length of time before the end of an off-peak period and that bimetal bar 75 flexed out of engagement with fixed contact member 77, as hereinbefore described, and that withdrawal of some of the hot water occurred before the end of an off-peak period, the coil 79 would be energized as hereinbefore described, with attendant reenergization of the heater 21 and heating of the water would again occur. The holding circuit hereinbefore described for the coil 79 is independent of the on and off switch moved continuously by the timer and is dependent only on the engagement 30 of bimetal bar 75 with contact 77. Should it, therefore, occur that a relatively large amount of hot water is withdrawn from the tank just before the end of an off-peak period, at which time contact bar 41 is moved out of engagement 35 with contacts 49 and 51, reenergization of the heater will have been effected, as above described, and such reenergization of the heater will continue until substantially all of the water in the tank is hot when flexing of bimetal bar 75 out 40 of engagement with contact 77 will open the holding circuit of coil 79 of the contactor so that my system is independent of the position of the timer-actuated switch initiating the operation, under the conditions set forth above.

I desire to point out that the elements shown in the various figures of the drawing are shown generally only and that all variations in design and construction may be made to provide a properly operative device giving the results hereinbefore set forth. All such modifications clearly coming within the scope of the appended claims are to be considered as being covered thereby.

I claim as my invention:

1. An off-peak water heating system for a tank having an electric heater, comprising a continuously operative timer, a switch controlling the energization of said electric heater adapted to be moved continuously by said timer in a given direction in a given path, a member in said path for actuating said switch from open to closed position, a thermal means on said tank responsive to the average tank water temperature adapted to move said switch-actuating member to engage said switch earlier in case the tank water temperature is low than in case it is high and a fixed member in said path for moving said switch to off position.

2. An off-peak water heating system for a tank having an electric heater, comprising means including an electromagnetic switch for controlling the energization of said heater, a continuously

operative timer, an on-and-off switch adapted to be moved continuously in a given direction in a circular path by said timer and effective to control the energization of said electromagnetic switch, a pin in said path for moving said timer-actuated switch into closed position to cause energization of said electromagnetic switch and of said electric heater in case less than all of the water in the tank is hot and means responsive to the heat content of the tank for moving said pin.

3. In an off-peak water heating system for a tank having an electric heater, an electromagnetic switch for controlling the energization of said heater, a continuously operative timer, an on-and-off switch adapted to be moved continuously in a given direction in a circular path by said timer and effective to control the energization of said electromagnetic switch, a pin in said path for moving said timer-actuated switch into closed position to cause energization of said electromagnetic switch and of said electric heater in case less than all of the water in the tank is hot, means responsive to the heat content of the tank for moving said pin and a thermally-actuable switch in the heater circuit for causing deenergization of said heater when substantially all of the water in the tank is hot.

4. In an off-peak water heating system for a tank having an electric heater, an electromagnetic switch and a thermally-actuable switch electrically connected in series circuit with each other and controlling severally the energization of the electric heater, an on-and-off switch for controlling the energization of said electromagnetic switch, a continuously operative timer adapted to move said on-and-off switch continuously in a given direction in a given path, means movable in a part of said path to a position depending on the amount of hot water in the tank to cause movement of said on-and-off switch into on position earlier in case the average tank water temperature is low than in case it is high and means having a fixed position in said path to cause movement of said on-and-off switch into off position, to cause energization of said electric heater after a given delay after the start of an off-peak period in case the average temperature of the water in the tank is above a predetermined average value, to cause deenergization of said heater when the average temperature of the water in the tank is above a higher predetermined average value, to cause reenergization of said heater in case withdrawal of hot water during the rest of an off-peak period causes a reduction of the average water temperature to below said first named predetermined value and to cause deenergization of said heater when the average temperature of the water in the tank is above said higher predetermined average value irrespective of the position of said on-and-off switch.

5. A system as set forth in claim 2 and including a normally open switch operable into momentarily closed position to cause energization of said electromagnetic switch and of said heater at any desired time during an on-peak period in case less than all of the water in the tank is hot, said energization of the heater continuing until substantially all of the water in the tank is hot.

HERMAN M. BIEBEL.
